UNITED STATES PATENT OFFICE

2,259,097

CIRCUIT BREAKER

James M. Anderson, Broomall, Pa., assignor to
General Electric Company, a corporation of
New York

Application January 5, 1940, Serial No. 312,530

19 Claims. (Cl. 200—116)

My invention relates to circuit breakers, more particularly to manually operated overload responsive circuit breakers, and has for its object a simple and reliable circuit breaker provided with means for resetting the thermal overload responsive means.

Another object of my invention is the provision of an auxiliary signal means which is operated to give a signal in the event of an overload insufficient to open the circuit breaker. This combination is especially useful in distribution transformers, the signal giving a visual indication which persists after the end of the predetermined overload causing the signal.

In carrying out my invention in one form, I provide a toggle linkage for moving the movable contact between its open and closed positions together with means for releasing the fixed end of the made toggle in response to a predetermined current to effect the opening of the circuit breaker. I also provide a latch for holding the toggle straightened which latch is released by the opening of the circuit breaker on overload whereupon the toggle is broken and the fixed end of the toggle returns to a position to be again secured by the current responsive means.

I also provide an auxiliary switch for controlling a signal circuit, which auxiliary switch is actuated by the operating member of the main circuit breaker contacts and is moved to a position to be held by the current responsive means when the main contacts are moved to their closed positions. This arrangement provides for movement of the auxiliary switch member to its latched position without opening the main circuit breaker in the event that the auxiliary switch is released by the current responsive means to operate the signal while the main contacts remain in their closed positions.

For a more complete understanding of my invention, reference should be had to the accompanying drawings, Fig. 1 of which is a side elevation view of a circuit breaker embodying my invention; Fig. 2 is a plan view of the device shown in Fig. 1; Fig. 3 is a view in perspective of the operating mechanism with certain parts enlarged for purposes of clarity; Figs. 4 and 5 are simplified views showing the operating mechanism respectively in the manual open and automatic open before automatic reset positions; while Fig. 6 is a fragmentary view showing the manually operated latch in the open circuit position.

Referring to the drawings, particularly Fig. 3 which shows the circuit breaker in its closed

position, the movable contacts 10 and 11 cooperating with suitable stationary contacts are secured to an insulating bar 12 which, in turn, is secured to an arm 13 having a stationary pivot 14. This arm 13 is provided with upstanding projections 15 to which are secured a pair of toggle links 16. These toggle links 16 are, in turn, secured at their other ends to a second pair of toggle links 17 which have their other ends normally fixed and secured pivotally to a bell crank lever 18 constituting a trip or release arm. A stationary pivot 19 is provided for the bell crank lever and its other end 20 extends upward and is normally secured by a rotatable trip shaft 21 having a slot 22 for passage of the upper end of the arm 20. This trip shaft, slot and release arm arrangement is substantially as described and claimed in U. S. Patent No. 2,067,797, issued on January 12, 1937, to Robert W. Smith.

With the circuit breaker in its closed circuit position, as shown in Figs. 1, 2 and 3, a relatively strong helical spring 23 applies a force tending to break the toggle links 16 and 17 upward and open the circuit breaker. It is prevented from doing this, however, by a latch member 24.

More specifically, the spring 23 surrounds a stationary pivot pin 25 and has one end held against a stationary stop 26. Its other end engages a cross bar 27 between two parallel links 28 and 29 which have their lower ends pivoted on the pivot 25. This bar 27 lies in a notch 30 in an arm 31 which is pivoted on the pivot 25 and forms with a complementary arm 32 an operating arm, the movable end of which is connected through a link 33 to the floating pivot 34 joining the toggle links 16 and 17. As shown, the link 33 is provided with a slot for the pivot 34 to permit the pin 34 to move downward slightly after the toggle is made. Preferably when the circuit breaker is in its closed position, the toggle links 16 rest on the stationary pin 34a, as indicated in dotted lines in Fig. 1. The notch 30 is large enough to give the pin 27 considerable freedom of movement about its pivot 25 with respect to the arms 31, 32. The pin 27, however, is forced by the spring 23 in a clockwise direction about its pivot as seen in the drawings against the right hand wall of the notch 30 whereby the spring exerts a force on the arm 31 tending to move it in a clockwise direction (Fig. 3) about the pivot 25.

Movement of the arms 31, 32 is prevented, however, by the latch 24 which has a projection 35 hooked over a pin 36 extending between the

arms 31, 32 at a point near their movable end. The latch 24 is pivoted on a stationary pivot 37 and is biased about its pivot by a helical spring 38 in a counterclockwise direction, i. e., in a direction to hold the latch 24 in latching position on the pin 36.

For manual opening of the circuit breaker, two arms 39 are depressed about the pivot 25 by an actuating plunger 40, i. e., moved in a clockwise direction, as seen in Fig. 3. This brings a cross connecting strap or bar 41 between the two arms 39 adjacent the pivot 25 into engagement with a projection 42 on the trip arm 24. Further depression of the arms 39, therefore, carries the trip arm 24 in a clockwise direction about its pivot 37 until the pin 36 is released. Thereupon the spring 23 throws the arms 31, 32 upward breaking the toggle links 16, 17 in an upward direction. This moves the switch arm 18 in a counterclockwise direction about its pivot 16 to its open position, the switch arm being biased to this position by the springs 42a. An extension 42b on the arm 18 engages the supporting structure to limit the opening movement of the arm 18. This open position of the mechanism is shown in Fig. 4.

This opening action is, furthermore, effected with a snap action by means of the springs 23, 42a and a spring 43 connecting a pin 44 joining the outer ends of the arms 39 with a pin 45 connecting the upper ends of the arms 28, 29. Thus, as the arms 39 are depressed, the spring 43 is stretched and when the latch 24 is moved to its released position, the springs snap the arms 28 and 29 and the parts connected thereto including the movable contacts 10, 11 to open circuit position.

The circuit breaker can be closed manually by pulling up on the member 40 to turn the arms 39 in a counterclockwise direction whereby the cross strap 41 engages with the cross pin 27 and forces the arms 28 and 29 in a counterclockwise direction against the force applied by the spring 23. It will be observed that the cross strap 41, as shown in Fig. 3, is secured to the arms 39 at its ends at points spaced from the pivot 25. Therefore, when the strap 41 engages the pin 27, these two parts as the member 40 is raised move together in a predetermined relation with respect to each other about the pivot 25. The pin 27 now engages the opposite side of the slot 30, i. e., the left hand side as seen in Fig. 3, and moves the arms 31, 32 downward whereby link 33 forces links 16, 17 downward to close the switch and to store energy in springs 42a, and puts the arms 31, 32 in a position such that the latch 35 again hooks over the pin 36, as shown in the drawing.

During this upward and downward movement of the arms 31, 32, the pin 36 (Fig. 6) rides on the curved edge 35a of the projection 35 on the latch 24, whereby the projection 35 is prevented from being moved by the spring 38 in a counterclockwise direction to a position under the pin 36. Such a condition would, of course, prevent the projection 35 from again hooking over the pin 36 when the arms 31, 32 are lowered. In other words, the curved edge 35a rests against the pin 36 while the arms 31, 32 are being raised and lowered so that the projection 35 is ready to move over the pin 36 and latch it when the arms reach their lowermost closed circuit position.

To effect the automatic opening of the device in response to the current through the contacts 10 or 11, two load responsive operating devices,

46 and 47 are connected respectively in circuit with these contacts. These devices preferably, as shown, are bimetallic thermostatic elements. They are each in the form of a hair pin with the open ends of the hair pin fixed each to a suitable support and with their looped ends extending upward so as to be free to move laterally in response to distortion of the thermostats. As shown clearly in Fig. 1, the thermostat 46 is secured to the base 48 at a point near the contact 10 so as to facilitate the connection of the movable arm of the contact through a flexible conductor 49 to one end of the thermostat. Also the thermostat 47 is similarly arranged 15 with respect to the contact 11. The thermostat from its point of support extends laterally with respect to the base and also toward the left-hand end, as seen in Figs. 1 and 2, at an angle with the base.

20 By means of this inclined arrangement of the thermostats, their movable ends are brought into position to engage projections 50 and 51 on the trip shaft 21 so as to turn the shaft clockwise in response to a predetermined current through the thermostats and thereby release the trip arm 20. When this occurs, the trip arm 20 moves in a clockwise direction, as seen in Fig. 3. The current responsive means is thus constituted by one or both of the thermostats and, in addition, the rotatable trip shaft 21 and the parts mechanically connecting it to the thermostats. The pivot 52 is somewhat lower than the pivot 19 so that a clockwise bias is applied to the trip arm by the switch opening springs 42a. This 25 allows the switch arm 18 to move to its open position and in so doing the cross part 53 on the switch arm engages a projection 54 on the trip member 24 whereby the trip member is moved clockwise on its pivot 37 to release the pin 36. At this instant the parts are in the relative positions indicated in Fig. 5 although they do not remain in these positions. Thereupon the arms 31, 32 move upward in accordance with their bias by the spring 23 and break the 30 toggle arms 16, 17 upward thereby returning the trip member 20 back to its latched position, shown in Fig. 4 of the drawings, where it is secured by the trip shaft 21 when the thermostats have cooled.

35 For purposes of adjustment to vary the current response of the circuit breaker, the projections 50 and 51 are mounted on hollow or tubular shafts 55 and 56 made of a suitable electrically insulating material such as a molded compound. Through these hollow shafts extends a metal rod 57 with an enlarged central part 21 provided with the latching slot 22. The insulating parts 55 and 56 carry projections 58 and 58a to which is secured a metal arm 59. On the outer end 40 of this arm is a button 60, preferably made of a molded compound, which is provided with a tapped bore cooperating with the threaded end of a rod 61. The lower end of this rod 61 pivotally engages the end of an arm 62 which is secured to the central metallic portion 21 of the trip shaft. A wire spring 63 applies a force 45 tending to separate the arms 59 and 62, which force is opposed by the connection formed by the rod 61.

50 Also the arm 62 is normally held in a predetermined position by a helical spring 64 (Fig. 1) having one end connected to a side frame member 65 and its other end connected to a projecting arm 66 on the arm 62. This spring pulls upward biasing the arm 62 as seen in Fig. 3, in a counter-

clockwise direction, and normally holding the end of the arm 66 against a stop 67 (Fig. 2) on the side plate 65.

Thus, when the button 60 is turned, the connecting rod 61 is lengthened or shortened as the case may be, and thereby the arm 59 and the hollow insulating shafts 55 and 56 as a unit are adjusted about the shaft 57. In this way the electrically insulating trip projections 50 and 51 are adjusted with respect to the ends of the thermostats so that the thermostats have a smaller or greater amount of movement required of them in order to engage the projections 50 and 51 and turn the trip shaft far enough to release the trip member 20. A further equalizing adjustment to compensate for variations in manufacture of the thermostats is provided by an adjustable insulated button 67a (Fig. 1) on the end of each thermostat, which button moves to engage the projections 50 and 51.

Also built into the circuit breaker is a bridging contact member 68 (Fig. 3), electrically separate from the circuit breaker described, which is normally held in open circuit position but which is released upon the occurrence of an overload current somewhat lower than that required to trip open the circuit breaker contacts 10 and 11. The object of this is to give an indication as by the lighting of a lamp or the ringing of a bell that an overload, although not a dangerous overload, exists. On heavier overloads, the contact member 68 will give indication as described, just prior to opening of breaker contacts 10, 11 while on short circuit 68 will indicate practically simultaneously with opening of the breaker contacts. If the circuit breaker is not opened, the signal indicates that the equipment has been subjected to some overload, while if the breaker be opened the signal indicates that there has been a heavy overload or short circuit.

This bridging contact member 68 is mounted for movement on an arm 68a, in turn mounted on the pivot 19. On the arm 68a is a projection 69 pivotally secured thereto on a pivot 70 and adjustable with relation thereto about the pivot by means of a screw 71. The upper end of this arm 69 normally engages a projection 72 carried by the arm 62 and, therefore, movable with the trip shaft. A helical spring 73 applies a biasing force to the bridging contact arm in a clockwise circuit closing direction as seen in Fig. 3. This spring 73 has one end 73a (Fig. 3) attached to the arm 68a, its other end 73b being suitably secured to a support for the parts (not shown in Fig. 3) in the manner of spring 38.

This projection 72 and the arm 69 are so arranged relatively that upon a predetermined movement of the trip shaft caused by a predetermined current, adjustment for which may be made by the screw 71, the projection 72 moves clockwise as seen in Fig. 3, sufficiently to release the arm 69 whereupon the bridging contact is moved by the spring 73 to bridge the two stationary contacts 74 and thereby give a signal, such as lighting a lamp 75, or ringing a bell. This indicates that an overload exists or has existed in the circuit although this overload may not have been sufficient to trip the breaker.

It is contemplated that this circuit breaker will be mounted in the tank of an outdoor service transformer and immersed in the transformer oil with the contacts 10 and 11 connected in the secondary circuit of the transformer. Thus the lamp 75, visible from the exterior of the transformer, gives an indication of overload although

the overload is not sufficient to damage the transformer or interrupt service. The operating rod 40 will extend out of the transformer tank so that the breaker can be operated manually. Moreover, in the event that the load continues to increase and the circuit breaker is tripped open, the bridging contact 68 stays in its closed circuit position until the circuit breaker is again closed. Therefore, if service is interrupted, the lamp gives an indication not only of a tripped circuit breaker, but also makes known the fact that there had been a heavy overload or short circuit on the line.

The bridging contact 68 is opened when the member 40 is pulled upward to close the circuit breaker, the contact 68 being operated by means of an operating rod 76 which extends loosely through an aperture in an extension 77 of the pin 45. Also this rod 76 has an offset 78 which, when the pin 45 is moved counterclockwise about its pivot 25, is engaged by the extension 77 and upon continued movement of the extension 77, the rod 76 returns the latch arm 69 to the latched position shown in the drawing, Fig. 3. In other words, the arm 69 may be and is pushed back under the projection 72, without tripping the circuit breaker, the bias of the spring 64 returning trip shaft 57 to full latching position after 69 is latched by 72. Obviously the contact 68 is opened in the same manner after its closure in response to an overload insufficient to open the main contacts 10 and 11. Thus it will be seen that this reopening or resetting of the auxiliary contact 68 has no effect on the main contacts 10 and 11 when these contacts are already closed, the main contacts simply remaining closed.

It is to provide for this resetting of the bridging signal contact 68 that the loose connection is provided between the arms 28, 29 and the arms 31, 32, this connection being formed by the pin 27 which moves in the elongated notch 30. Preferably a similar slot is provided in the arm 32. Thus, after the switch 68 has been opened as previously described the arms 28 and 29 are moved clockwise by the spring 23 when the closing handle or member 40 is released, until the pin 27 engages the right-hand end of the notch, as viewed in Fig. 3. This moves the projection 77 clockwise away from the shoulder 78 so that when the arm 69 is again released, it is free to turn and bring the bridging contact 68 into its closed circuit position.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

What I claim as new and desire to secure by Letters Patent of the United States is:

1. A circuit breaker comprising a switch member, an operating member connected to move said switch member between its open and closed circuit positions, a spring for biasing said operating member to cause movement of said switch member to said open circuit position, a latch for holding said operating member against the force applied by said spring, a second operating member mounted for movement in one direction to move said first operating member to a position to be held by said latch and in another direction independently of said first operating member to move said latch to release said first oper-

ating member, and current responsive means for causing movement of said switch member to its open circuit position independently of said first operating member.

2. A circuit breaker comprising a switch member, an operating member connected to move said switch member between its open and closed circuit positions, a spring for biasing said operating member to cause movement of said switch member to said open circuit position, a latch for holding said operating member against the force applied by said spring, a second operating member mounted for movement in one direction to move said first operating member to a position to be held by said latch and in another direction independently of said first operating member to move said latch to release said first operating member, and current responsive means for causing movement of said switch member to its open circuit position independently of said first operating member, said switch member being arranged to move said latch to a position to release said first operating member when said switch moves to its open circuit position.

3. A circuit breaker comprising a switch member, spring means biasing said switch member to its open circuit position, a release member, current responsive means normally holding said release member in a predetermined position, a toggle having one end connected to said switch member and its other end connected to be held normally by said release member, an operating member connected to make and break said toggle so as to move said switch member between its open and closed circuit positions, a toggle spring for biasing said operating member to a position to break said toggle whereupon said switch member moves to said open circuit position, a latch for holding said operating member against the force applied by said toggle spring, and a second operating member mounted for movement in one direction to move said first operating member to a position to be held by said latch and in another direction to move said latch to release said first operating member.

4. A circuit breaker comprising a switch arm, spring means biasing said switch arm to its open circuit position, a release arm, current responsive means normally holding said release arm in a predetermined position, a toggle having one end connected to said switch arm and its other end connected to be held normally by said release arm, an operating member connected to make and break said toggle so as to move said switch arm between its closed and open circuit positions, a toggle spring for biasing said operating member to a position to break said toggle whereupon said switch arm moves to said open circuit position, a latch for holding said operating member against the force applied by said toggle spring, and a second operating member mounted for movement in one direction to move said first operating member to a position to be held by said latch and in another direction to move said latch to release said first operating member, said switch arm being arranged to move said latch to a position to release said first operating member when said switch arm moves to its open circuit position so that when said switch arm is opened by movement of said release arm in response to a predetermined current said toggle spring moves said operating arm to break said toggle and thereby return said release arm to said predetermined position.

5. A circuit breaker comprising a switch arm, spring means biasing said switch arm to its open circuit position, a release arm, a toggle having one end connected to said switch arm and its other end connected to said release arm, thermal current responsive means normally holding said release arm in a predetermined position against the bias of said switch arm to its open position, an operating arm connected to make and break said toggle so as to move said switch arm between its open and closed circuit positions, a toggle spring for biasing said operating arm to a position to break said toggle and move said switch arm to said open circuit position, a pivoted latch for holding said operating arm against the force applied by said toggle spring, manual operating means for moving said latch to a position to release said operating arm whereby said switch arm is opened with a snap action, and means carried by said switch arm for moving said latch to its released position when said switch arm is opened by said thermal current responsive means in response to a predetermined current whereupon said toggle spring moves said operating arm to break said toggle and thereby return said current responsive release arm to a position to be secured by said thermal means.

6. A circuit breaker comprising a switch arm, spring means biasing said switch arm to its open circuit position, a release arm, a toggle having one end connected to said switch arm and its other end connected to said release arm, means normally holding said release arm in a predetermined position against the bias of said switch arm to its open position, thermal current responsive means for causing movement of said holding means to free said release arm, an operating arm connected to said toggle so as to make and break said toggle and thereby move said switch arm between its open and closed circuit positions, a toggle spring for biasing said operating arm for movement to break said toggle and move said switch arm to said open circuit position, a pivoted latch for holding said operating arm against the force applied by said toggle spring, a second operating arm, means connecting said operating arms for movement together to make said toggle when said second arm is moved in one direction, a second spring connecting said operating arms so as to be tensioned by movement of said second operating arm in the other direction, means carried by said second operating arm for moving said latch to its released position when said second arm is moved in said second direction whereby said switch arm is opened with a snap action, and means carried by said switch arm for moving said latch to its released position when said switch arm moves to its open circuit position so that when said switch arm is opened by said thermal current responsive means, said toggle spring moves said operating arm to break said toggle and thereby return said current responsive release arm to a position to be secured by said thermal means.

7. A circuit breaker comprising a switch member, a spring for biasing said switch member to an open circuit position, an operating member connected to move said switch member between its open and closed circuit positions, a second operating member, a lost motion connection between said operating members whereby said second operating member is movable to operate said first operating member, a second spring for biasing said second operating member

relative to said first operating member in a direction opposite to its circuit closing direction of movement, a current responsive means for causing movement of said switch member to its open circuit position independently of said first operating member, a second switch member, a signal device controlled by said second switch member, a spring for biasing said second switch member to a predetermined position to operate said signal device, latching means for securing said second switch member in another position, an operating connection between said latching means and said current responsive means whereby said latching means is moved to release said second switch member in response to a lower current than that required to cause movement of said first switch member to its open circuit position, a connection between said second operating member and said second switch member for moving said second switch member to a position to be secured by said latching means concurrently with movement of said first operating member to its closed circuit position, said second spring thereafter moving said second operating member independently of said first operating member to release said second switch member.

8. A circuit breaker comprising a switch arm, a spring biasing said switch arm to its open circuit position, an operating member connected to move said switch arm between its open and closed circuit positions, a second operating member, a lost motion connection between said operating members, a spring for biasing said second operating member to cause movement of said switch arm to said open circuit position, a latch for holding said first operating member against the force applied by said spring, current responsive means for causing movement of said switch arm to its open circuit position independently of said first operating member, said switch arm being arranged to move said latch to a position to release said first operating member when said switch arm moves to its open circuit position, a second contact arm, a signal device controlled by said second contact arm, a second spring for biasing said second contact arm to a predetermined position, latching means for securing said second contact arm in another position, an operating connection between said latching means and said current responsive means whereby said latching means is moved to release said second switch arm in response to a lower current than that required to release said first switch arm, a connection between said second operating member and said second switch arm for moving said second switch arm to a position to be secured by said latching means simultaneously with movement of said first operating member to a position to be held by said latch, said first spring thereafter moving said second operating member independently of said first operating member to release said second switch arm.

9. A circuit breaker comprising a switch arm, an operating member connected to move said switch arm between its open and closed circuit positions, a second operating member, a lost motion connection between said operating members, a spring for biasing said second operating member to move said switch arm to said open circuit position, a latch for holding said first operating member against the force applied by said spring, a third operating member movable in one direction to engage said second operating

member and thereby move said second operating member to a position to be held by said latch and movable in another direction independently of said second operating member to move said latch to release said first operating member, current responsive means for causing movement of said switch arm to its open circuit position independently of said first operating member, said switch arm being arranged to move said latch to a position to release said first operating member when said switch arm moves to its open circuit position, a second contact arm, a signal device controlled by said second switch arm, a second spring for biasing said second switch arm to a predetermined position, latching means for securing said second switch arm in another position, an operating connection between said latching means and said current responsive means whereby said latching means is moved to release said second switch arm in response to a lower current than that required to move said first switch arm to its open circuit position, a connection between said second operating member and said second switch arm for moving said second switch arm to a position to be secured by said latching means simultaneously with movement of said first operating member to a position to be held by said latch, said first spring thereafter moving said second operating member independently of said first operating member to release said second switch arm.

10. A circuit breaker comprising a main switch member, an auxiliary switch member, an operating arm for each of said switch members, said arms being mounted for movement on a common pivot and being connected together for limited angular movement with respect to each other, an operating member engaging said auxiliary switch operating arm for movement of said arms together in one direction about said pivot to close said main switch member and operate said auxiliary switch member to one position, latching means holding said main switch operating arm in said closed circuit position, means biasing said auxiliary switch operating arm in an opposite direction away from said auxiliary switch member to provide for movement of said auxiliary switch member independently of said auxiliary switch operating arm, and current responsive latching means for normally holding said auxiliary switch member in said one position.

11. A circuit breaker comprising a main switch member, an auxiliary switch member, an operating arm for each of said switch members, said arms being mounted for movement on a common pivot and being connected together for limited angular movement with respect to each other, an operating member engaging said auxiliary switch operating arm for movement of said arms together in one direction about said pivot to close said main switch member and open said auxiliary switch member, latching means holding said main switch operating arm in said closed circuit position, means biasing said auxiliary switch operating arm in an opposite direction away from said auxiliary switch member to provide for closing movement of said auxiliary switch member independently of said auxiliary switch operating arm, and current responsive latching means for normally holding said auxiliary switch member in an open circuit position, and current responsive means for causing movement of said latching means to release said auxiliary switch member.

12. A circuit breaker comprising a main switch

member, an auxiliary switch member, an operating arm for each of said switch members, said arms being mounted for movement on a common pivot and being connected together for limited angular movement with respect to each other, an operating member engaging said auxiliary switch operating arm for movement of said arms together in one direction about said pivot to close said main switch member and open said auxiliary switch member, latching means holding said main switch operating arm in said closed circuit position, means biasing said auxiliary switch operating arm in an opposite direction away from said auxiliary switch member to provide for closing movement of said auxiliary switch member independently of said auxiliary switch operating arm, and current responsive latching means for normally holding said auxiliary switch member in an open circuit position and said main switch member in a closed position, said latching means being arranged to release said auxiliary switch member in response to an increased current before said main switch member is released.

13. A circuit breaker comprising a pair of switch members, an operating member connected to move said switch members between open and closed circuit positions, a trip member mounted for movement on a pivot axis, a latch member normally held by said trip member to hold said switch members in closed circuit positions but released for opening movement of said switch members when said trip member is turned on its pivot axis, an adjustment member mounted for movement on said pivot axis, a pair of thermostats arranged to engage said adjustment member and connected respectively in circuit with said switch members, a member adjustably secured to each of said thermostats and engaging said adjustment member for movement of said adjustment member when said thermostats are heated by the current therethrough, and an adjustable connection between said adjustment member and said trip member providing for independent adjustment of said adjustment member with respect to said trip member and for movement of said trip member with said insulating member by said thermostats.

14. A circuit breaker comprising a pair of switch members, an operating member connected to move said switch members between open and closed circuit positions, a trip shaft provided with a slot, a latch member normally engaging and held by said shaft to hold said switch members in closed circuit positions but released for opening movement of said switch members when said shaft is rotated to bring said slot into register with said latch member, an insulating member made of electrically insulating material mounted for rotation on said shaft, a pair of arms on said insulating member, a pair of thermostats arranged opposite said arms and connected respectively in circuit with said switch members, a member adjustably secured to each of said thermostats and engaging said insulating arms for rotation of said insulating member when said thermostats are heated by the current therethrough, and an adjustable connection between said insulating member and said shaft providing for rotative adjustment of said arms on said shaft and for rotation of said shaft with said insulating member by said thermostats.

15. A circuit breaker comprising a main switch member, an auxiliary switch member, means biasing said switch members independently to

predetermined positions, current responsive means for normally securing said switch members in other positions against their biases, said current responsive means being arranged to release said auxiliary switch member in response to a lower current than required for the release of said main switch member, an operating member, and connections between said operating member and said switch members providing for movement of said switch members to said predetermined positions independently of said operating member and for movement of said operating member in a first direction to move said main and auxiliary switch members to said other positions against their biases, said operating member being movable in a second direction to cause movement of said main switch member to said predetermined position independently of said auxiliary switch member.

20 16. A circuit breaker comprising a main switch member, an auxiliary switch member, independently movable main and auxiliary latch members connected respectively to said main and auxiliary switch members, means biasing said switch members independently to predetermined positions, current responsive means for normally securing said latch members in predetermined positions in which said switch members are held in other positions against their biases, said current responsive means being arranged to release said auxiliary latch member for operation of said auxiliary switch member in accordance with its bias in response to a lower current than required for the release of said main latch member, an operating member, and connections between said operating member and said switch members providing for movement of said switch members to said predetermined positions independently of said operating member and for movement of said operating member in a first direction to move said main and auxiliary switch members to said other positions against their biases and thereby to move said auxiliary latch member to a position to be held by said current responsive means, 45 said operating member being movable in a second direction to cause movement of said main switch member to said predetermined position independently of said auxiliary switch member.

17. A circuit breaker comprising a main switch member, an auxiliary switch member, means biasing said main switch member to its open circuit position and biasing said auxiliary switch member to a first position, current responsive means for normally securing said switch members in their closed and first positions, respectively, against their biases, said current responsive means being arranged to release said auxiliary switch member in response to a lower current than required for the release of said main switch member, an operating member, a connection between said operating member and said main switch member providing for opening movement of said main switch member independently of said operating member and for movement of said operating member in a first direction to move said main switch member to its closed circuit position, a lost motion connection between said operating member and said auxiliary switch member providing for movement of said auxiliary switch member to a second position to be held by said current responsive means upon movement of said operating member in said first direction, a spring for moving said operating member a predetermined amount in a second direction to provide for movement of said aux-

iliary switch member to said first position independently of said operating member, said operating member being movable farther in said second direction to cause movement of said main switch member to its open position independently of said auxiliary switch member.

18. A circuit breaker comprising a switch member, spring means biasing said switch member to its open circuit position, a latch member, current responsive means normally holding said latch member in a predetermined position, linkage means connecting said switch member to said latch member to maintain said switch member in its closed circuit position, an operating member connected to said linkage means so as to move said switch member between its closed and open circuit positions, spring means for biasing said operating member to a position to move said switch member to its open circuit position and move said latch member to a position to be held by said current responsive means, a second latch member for holding said operating member against said spring means, said second latch member being arranged to be moved by said switch member to release said operating member when said switch member moves to its open circuit position upon release of said latch member by said current responsive means, whereby said first latch member is returned to a position to be held by said current responsive means.

19. A circuit breaker comprising a switch member, spring means biasing said switch member to its open circuit position, a latch member,

current responsive means normally holding said latch member in a predetermined position, linkage means connecting said switch member to said latch member to maintain said switch member in its closed circuit position, an operating member connected to said linkage means so as to move said switch member between its closed and open circuit positions, spring means for biasing said operating member to a position to move said switch member to its open circuit position and move said latch member to a position to be held by said current responsive means, a second latch member for holding said operating member against said spring means, said second latch member being arranged to be moved by said switch member to release said operating member when said switch member moves to its open circuit position upon release of said first latch member by said current responsive means, whereby said first latch member is returned to a position to be held by said current responsive means, a second switch member biased to a predetermined position and normally held in a second position by said current responsive means and a second operating member having a limited freedom of movement with respect to said first operating member and movable to move said auxiliary switch member to its predetermined position and concurrently therewith move said first operating member to close said main switch member.
